UNITED STATES PATENT OFFICE

2,465,395

LONG AND SHORT DELAY FUSE

George M. O'Rear, United States Navy

Application May 11, 1938, Serial No. 207,314

6 Claims. (Cl. 102—74)

(Granted under the act of March 3, 1883, as
amended April 30, 1928; 370 O. G. 757)

1

This invention relates to a fuze, especially adapted for use in major caliber projectiles, so constructed as to cause the burst of the projectile after penetration of either thin or thick protective walls.

Among the objects of this invention are:

To provide a fuze that will cause a burst after a delay dependent upon the thickness of the plate penetrated by a projectile wherein the fuze is mounted;

To provide a fuze that will cause bursting of a projectile within the beam limits of a light armored vessel, but upon impact with heavy armor will delay the burst until after penetration;

To provide a fuze that will, in case of an initial light impact and subsequent heavy impact delay the burst until after cessation of the deceleration due to the heavy impact;

To provide a fuze that will cause the burst of a projectile with a high order of detonation after penetrating armor plate.

In the drawings:

Fig. 1 is a longitudinal section on the axis of a fuze embodying the present invention;

Fig. 2 is a longitudinal section of the elements for firing the charge of a projectile after a short delay;

Fig. 3 is a transverse section on the line 3—3, Fig. 1;

Fig. 4 is a longitudinal section of elements for firing the long delay ignition means.

In order to inflict the greatest possible damage upon a target by the explosion of a projectile, it is necessary that the burst be delayed until after the protective armor on the target has been penetrated. It is obvious that if the same type of fuze is to be effective against both light and heavy craft there must be some provision for causing the burst after the penetration of light armor plate and within a relatively short distance, as when the target is a destroyer, and also to delay the burst until after penetration of heavy armor and travel of the projectile some distance into the space behind the armor to reach the vitals of the ship. Likewise, it is desirable that the fuze be so constructed that if a target have a light protective armor backed by a heavier armor, that the burst should not occur until after penetration of the heavy armor. These requirements are met in a fuze constructed according to the present invention.

The fuze body 5 is provided with a longitudinal bore having portions of different diameters to accommodate the several elements that will be hereinafter set forth. Forwardly of the tracer 6

2

is the rear firing pin carrier 7 wherein is slidably mounted a firing pin 8 having an enlarged rear portion 9 in which is a groove 10 and with a conical end portion 11. Engaged in the slot 10 are the detents 12 that are freed from the groove 10 by centrifugal force of rotation of the fuze during flight and when the firing pin is thus freed it creeps forward and allows the balls 13 to drop down behind the end portion 11 and so lock the 10 firing pin 8 in its forward or armed position. It is apparent that should any force act upon the firing pin 8 tending to move it backwardly after having been thus locked that the balls 13 would be acted upon simultaneously and would mutually 15 prevent each other from being forced back into their original position which would permit the firing pin 8 to be moved out of the armed position.

Forwardly of the firing pin carrier 7 is the rear plunger 14 having an annular groove 15 adjacent its forward end and in which groove are seated the balls 16 that engage the shoulder 17 on body 5 and thus lock the rear plunger 14 in its forward-most position against the pressure of spring 18 that tends to move the rear plunger backwardly. 20 Disposed in the plunger 14 is a firing assembly 50 comprising a primer 19 that is ignited by contact with firing pin 8 under proper conditions. The gases produced by the burning of primer 19 cause the detonation of primer 22, the resultant 25 hot gases passing through baffle 23 to short delay pellet 24 whence the ignition is propagated by a body 25 of powder to detonator 26 and thence by detonator lead-outs 27 to booster charges 28.

The forward plunger 29 has at its rear end an 30 annular flange 30 disposed around the balls 16 to act as a ball retainer and thereby prevents displacement of the balls 16 except upon impact after flight. Detents 31 lock the plunger 29 in its 35 rearmost portion but are released from engagement with the plunger by rotation of the fuze during flight. A shear pin 32 prevents creeping of plunger 29 after release of the detents 31 until the pin 32 is sheared by movement of plunger 29 upon impact. An expandable ring 33 is disposed 40 in a groove in plunger 29 and moves outwardly 45 into groove 34 in the body 5 to lock the plunger 29 in firing position with regard to firing pin 35 carried by cap 36.

Mounted in forward plunger 29 is a second 50 firing assembly 51, shown in sectional detail in Fig. 4. This includes a primer 37 that is struck by firing pin 35 and the gases therefrom pass through baffle 38 to delay pellet 39 which in turn ignites a powder charge 40 whence the ignition 55 is propagated to long delay detonator 41 that in

turn ignites the booster charges 42. The gases resulting from the firing of the primers 22 and 37 are prevented from escaping into other parts of the fuze mechanism by obturating rings 43 of lead or other readily deformable metal that are squeezed out into tight sealing contact with the respective plungers, after the baffles 23 and 38 are assembled in the respective plungers together with the members wherein the delay elements 24 and 39 are disposed.

The operation of my novel fuze is as follows:

When fired and while the set back force is acting the firing pin 8 is maintained in the unarmed position as shown in Fig. 1, and rear plunger 14 is kept in its forwardmost or unarmed position by the lock effected through engagement of balls 16 in the groove 15 and against the shoulder 17. After the setback ceases to act the detents 12 and 31 are moved outwardly by centrifugal force and disengage from the elements respectively locked thereby. The firing pin 8 creeps forward into the armed position and the balls 16 move out and drop down behind the portion 11 and thus lock the firing pin 8 in the armed position. Movement of plungers 14 and 29 is prevented during flight by the shear wire 32 which retains plunger 29 in position to hold balls 16 in groove 15. Upon striking the target the firing pin 8 is moved forward if it has not already crept into the firing position, forward plunger 29 is moved ahead shearing pin 32, and releasing the balls 16 thereby leaving the rear plunger 14 free to be moved back to strike primer 19 upon firing pin 8 under the force exerted by spring 18. However, the inertia of rear plunger 14 holds it forward against the action of spring 18 while the projectile is undergoing deceleration in its passage through an armor plate. If the armor plate be light the decelerating force ceases to act and spring 18 drives rear plunger 14 backwardly and the primer 19 is fired. The delay intervening between the firing of primer 19 and the detonation of the charge through detonator 26 and booster 23 is sufficiently short that the burst will occur within the beam width of a destroyer.

However if the armor plate be heavy the plunger 14 will be held in its forward position by inertia but the primer 37 will have been fired by firing pin 35 and the long delay burning time of detonator 41 will result in the burst after passage through the armor and travel of some little distance therebeyond. It may be that if the armor is very heavy delay element 39 will have burned so far by the time penetration is effected that the short delay of the elements carried by rear plunger 14 will become effective after the deceleration has ceased so that both the firing means will simultaneously act to cause the burst.

In the event that a light plate is penetrated and very soon thereafter a heavy plate is encountered the plunger 14 will not have been moved back into firing position by spring 18 before the deceleration of the heavy impact again moves plunger 14 forwardly and prevents firing of the primer 19. The long delay of the igniting elements in forward plunger 29 will permit penetration of the heavy plate before the burst.

It is thus apparent that a fuze embodying my present invention is effective under various conditions of impact and against substantially a types of targets. The plungers 14 and 29 are provided with pins 44 engaged in corresponding grooves in body 5 to maintain the detonator lead-outs respectively in alignment with the booster charges to be ignited thereby. It will be ob-

served that the detonator lead-outs are not in registry with the respectively cooperating booster charges until the plungers have been moved into the firing position and thus the bursting charge 5 of a projectile provided with my fuze would not be detonated even though, for some reason or other, a primer were struck or a detonator ignited, except when in the firing position of the plunger and this can occur only after firing of 10 the projectile.

The invention herein described and claimed may be used and/or manufactured by or for the Government of the United States of America for governmental purposes without the payment of 15 any royalties thereon or therefor.

I claim:

1. A projectile fuze, comprising a fuze body, a rear plunger slidably mounted therein, said plunger having an annular groove adjacent its forward end, a detonator charge and associated lead-outs in said plunger; means to ignite said detonator including a first primer, a second primer disposed to detonate said first primer when said second primer is fired; a spring under compression to move said plunger backward, balls in said groove, a shoulder on said body engaging said balls to lock said plunger against movement by said spring; a first firing pin forwardly slidably in said body to fire said second primer, centrifugally releasable means holding said first firing pin normally in inoperative position, means to lock said firing pin in firing position; booster charges in said body to register with said lead-outs when said plunger is moved back against said first firing pin by said spring; a forward plunger slidably in said body, a rearwardly projecting annular flange on said forward plunger to retain said balls in said groove when said forward plunger is at its rearmost position, centrifugally releasable means to retain said forward plunger normally in said position, a shear wire engaging said body and said forward plunger to prevent creep of said forward plunger after said centrifugally releasable means have been released, a second detonator and associated lead-outs and a third primer in said forward plunger, means to propagate ignition from said third primer to said second detonator including material requiring a longer burning time than the ignition time of said first detonator; a cap on the forward end of said body, a second firing pin in said cap to fire said third primer when said forward plunger is moved at impact of a projectile carrying said fuze, means to lock said forward plunger in position when said third primer is fired, and booster charges in said body to register with said second lead-outs when said forward plunger is so locked.

2. A projectile fuze, comprising a fuze body, a rear plunger slidably mounted therein, said plunger having an annular groove adjacent its forward end, a forward plunger slidably mounted in said body, centrifugally releasable means normally retaining said forward plunger in its rearmost position, balls in said groove, a rearwardly extending flange on said forward plunger to retain said balls in said groove, a shoulder on said body engaged by said balls to hold said rear plunger in its forwardmost position, a spring 60 acting to move said rear plunger rearwardly when released by forward movement of said forward plunger, a detonator charge and short delay means including a primer to fire said detonator in said rear plunger, a firing pin mounted to be 65 slidable into position to fire said primer, cen-

trifugally releasable means to hold said firing pin normally out of the firing position, means to lock said firing pin in the firing position after release, a detonator and long delay means including a primer to ignite said detonator carried by said forward plunger, a cap on the forward end of said body, a firing pin carried by said cap to fire the primer in said forward plunger when moved forward by impact of a projectile whereby said fuse is carried, a shear pin engaging said body and said forward plunger to prevent creep of said forward plunger, means to lock said forward plunger in the firing position, and booster charges disposed to be fired respectively by said detonators when said plungers are in their respective firing positions.

3. A projectile fuze, comprising a fuze body, a rear plunger slidably mounted therein, said plunger having an annular groove adjacent its forward end, a forward plunger slidably mounted in said body, centrifugally releasable means normally retaining said forward plunger in its rearmost position, balls in said groove, a rearwardly extending flange on said forward plunger to retain said balls in said groove, a shoulder on said body engaged by said balls to hold said rear plunger in its forwardmost position, a spring acting to move said rear plunger rearwardly when released by forward movement of said forward plunger, booster charges in said body, a primer carried by said rear plunger, short delay means to propagate ignition from said primer to said charges, a firing pin slidably into position to fire said primer, centrifugally releasable means to retain said firing pin normally out of firing position, a primer carried by said forward plunger, a firing pin disposed to fire the primer in said forward plunger when moved forwardly, other booster charges, long delay means to propagate ignition from the primer in said forward plunger to said other charges, and a shear pin engaging said forward plunger and said body to prevent creep of said forward plunger after release of said centrifugally releasable means.

4. A projectile fuze, comprising a fuze body, a rear plunger and a forward plunger slidably mounted therein, centrifugally releasable means normally holding said forward plunger in its rearmost position, a shear pin engaging said body and said forward plunger to prevent creep of said forward plunger after release of said releasable means, a rearwardly extending flange on said forward plunger, means cooperating with said flange to lock said rear plunger in its forwardmost position, a spring acting to move said rear plunger rearwardly when released by forward movement of said forward plunger, booster charges, a primer carried by said rear plunger, a firing pin, means normally holding said firing pin in unarmed position but releasable by rotation of said fuze during flight, said firing pin being moved into position to fire said primer not later than impact after flight, short delay means to propagate ignition from said primer to said charges, a primer car-

ried by said forward plunger, a firing pin disposed to fire said primer upon forward movement of said forward plunger at impact, other booster charges, long delay means to propagate ignition from the primer in said forward plunger to said other charges, and means to lock said forward plunger in firing position.

5. A projectile fuze, comprising a fuze body, a rear plunger and a forward plunger slidably mounted therein, centrifugally releasable means normally holding said forward plunger in its rearmost position, a shear pin engaging said body and said forward plunger to prevent creep of said forward plunger after release of said releasable means, a rearwardly extending flange on said forward plunger, means cooperating with said flange to lock said rear plunger in its forwardmost position, a spring acting to move said rear plunger rearwardly when released by forward movement of said forward plunger, a primer carried by said rear plunger, a firing pin, means normally holding said firing pin in unarmed position but releasable by rotation of said fuze during flight, said firing pin being moved into position to fire said primer not later than impact after flight, short delay ignition propagating means ignitable by said primer, a primer carried by said forward plunger, a firing pin disposed to fire said primer upon forward movement of said forward plunger at impact, long delay ignition propagating means ignitable by the primer in said forward plunger, and means to lock said forward plunger in firing position.

6. A projectile fuze, comprising a fuze body, a rear plunger and a forward plunger slidably mounted therein, means releasable by rotation of said body during flight to lock said forward plunger in its rearmost position, means including a portion on said forward plunger to lock said rear plunger in its forwardmost position, means to move said rear plunger backwardly when released, a primer in each plunger, a firing pin disposed to fire the one primer upon forward movement of said forward plunger and a second firing pin to fire the other primer upon backward movement of said rear plunger, short delay ignition propagating means ignitable by the primer in said rear plunger, and long delay ignition propagating means ignitable by the primer in said forward plunger.
